PORTABLE FLEXIBLE BODY-MASSAGE DEVICE

Chester M. Haworth, Jr., 4002 S. Clay St., Denver, Colo.
80101, and Frank R. Larmer, 10613 W. 101 Terrace,
Overland Park, Kans. 66214

Filed Feb. 9, 1972, Ser. No. 225,010

Term of patent 14 years

Int. Cl. D24—04

U.S. Cl. D83—1 T

FIG. 1 is a front view of the portable flexible body-massage device in a fully extended position showing our new design;

FIG. 2 is a side view thereof also in the extended position; and

FIG. 3 is an end view thereof.

We claim:

The ornamental design for a portable flexible body-massage device, as shown and described.
